UNITED STATES PATENT OFFICE

168,428

KNIFE AND FORK HOLDER

William R. Vermillion, Kansas City, Mo.

Application September 15, 1952, Serial No. 21,457

Term of patent 3½ years

(Cl. D44—29)

To all whom it may concern:

Be it known that I, William R. Vermillion, a citizen of the United States, residing at Kansas City, county of Jackson and State of Missouri, have invented a new, original, and ornamental Design for a Knife and Fork Holder, of which the following is a specification, reference being had to the accompanying drawing, forming a part hereof.

In the drawing:

Figures 3 and 4 are cross-sectional views of the same, representing sections taken on the lines 3—3 and 4—4, respectively, of Figure 1.

I claim:

The ornamental design for a knife and fork holder, substantially as shown.

WILLIAM R. VERMILLION.
